(57) **CLAIM**

The ornamental design for an open-configured computer docking assembly with two pivot arms, as shown and described.

DESCRIPTION

FIG. 1 is a perspective view from a side of a computer docking assembly with two pivot arms in an open configuration.

FIG. 2 is an end elevational of the invention shown in FIG. 1.

FIG. 3 is another end elevational view of the invention, opposed to the end shown in FIG. 2.

FIG. 4 is a side elevational view of the invention.

FIG. 5 is another side elevational view of the invention, opposed to the side shown in FIG. 4.

FIG. 6 is a top plan view of the invention; and,

FIG. 7 is a bottom plan view of the invention.
